KRUPP AKTIENGESELLSCHAFT, OF ESSEN-ON-THE-RUHR, GERMANY.

GUN-SIGHTING DEVICE.

1,041,102.

Specification of Letters Patent.

Patented Oct. 15, 1912.

Application filed October 15, 1910. Serial No. 587,260.

To all whom it may concern:

Be it known that I, HEINRICH KORRODI, a citizen of Switzerland, and a resident of Bern-Kirchenfeld, Switzerland, have invented certain new and useful Improvements in Gun-Sighting Devices, of which the following is a specification.

The present invention relates to gun sighting devices, in which the sight line, for the purpose of eliminating the effect of the inclined position of the wheels, may be swung about an axis, and may be laid parallel to the direction given the gun axis; and aims at the production of a sighting device of this kind, which is of a particularly simple and concise construction. This object is, in accordance with the present invention, attained by letting the oscillating axis of the sight-line coincide with the pivot axis of a gear, intended for setting the sight in the firing angle corresponding to the range.

An embodiment of the invention is shown on the drawing as applied to a recoil gun carriage, having an attachment sighting device, in which the driving gear, used for setting the sight in the firing angle, corresponding to the range, is connected with the driving member of the gun elevating gear mechanism by means of shafting. Recoil gun carriages of this kind have for instance, been described in the Patent No. 809,818.

In the drawing, Figure 1 shows a rear view, partly in section, of the attachment sighting device with associated parts of the recoil gun carriage; Fig. 2 is a side view, partly in section of Fig. 1; Fig. 3 is a section on line 3—3 of Fig. 2, seen from the right; and Fig. 4 is a detail of the gear intended for setting the firing angle corresponding to the range.

The gun barrel is mounted in the usual manner on the cradle B, which rests with its horizontal trunnions (not shown) in bearings on the carriage proper C and may be oscillated thereon. Between cradle and carriage is a screw elevating gear, which can be operated by means of two hand wheels D and E, independent of each other. Of these two hand wheels, the one E is mounted on the carriage C, and the other one, D, on a projection f¹ from a bracket F, carrying the attachment sight device, and being rigidly attached to the cradle B. This bracket is made hollow and placed on one side near the breech end A¹ of the gun,

and carries the elevating sleeve G in which is guided an arcuate sight-bar H, having the telescope J on top, which sleeve is so mounted that it can oscillate, for the purpose of eliminating the effect of the inclined position of the carriage wheels. To accomplish this, the arm F is provided with an arcuate guide-groove f², running in a plane at right angles to the gun axis; and the elevating sleeve G is provided with a guiding rib g¹, correspondingly shaped to, and running in the groove f². The device is moreover so arranged, that the oscillating axis of the elevating sleeve, coinciding with the guide-groove f², is parallel to the gun axis. In order to make the connection between the elevating sleeve G and the bracket F secure, a bayonet lock is provided (see Figs. 2 and 3) in which the elevating sleeve G is provided with a boss g², coaxial with its oscillating axis, having diametrically oppositely placed annular collars g³ at the edge of the boss g²; and by supplying the bracket F with diametrically oppositely interrupted annular collars f⁴ that fit the boss g² and engage behind the collars g³ in the locked position. The two interruptions g⁴ (Fig. 3) between the collars g³, permit of the insertion of the collars f⁴ into the boss g², when the elevating sleeve G is turned about 90° to the mean position represented in the drawing. With the elevating sleeve G in its working position (as shown on the drawing) a worm K is in mesh with the toothed segment g⁵ of the guiding rib g¹; so that the elevating sleeve G by turning the worm K, which is mounted in the bracket F, may be oscillated sufficiently to counteract the effect of the inclination of the wheels. A shaft M is mounted in the bracket F, coaxial with the circular guide-groove f², the end of this shaft nearest to the sight bar H, carrying a spiral gear m¹, which projects into the bored out space g⁶ (Fig. 2) coaxial with the boss g², and meshes with the toothed arc h¹ of the sight-bar H. The form of the spiral to which the actuating rib m² of the spiral gear is laid out (see Fig. 4) is chosen to have a shape of the least possible deviation from a circle. The shaft M is driven by a bevel wheel N rigidly attached thereto and situated in the hollow of the bracket F; and a second bevel wheel P, meshing with the first one, is mounted in the bracket F. From the latter wheel ball-jointed shafting

leads to the hand wheel D of the gun elevating gear. This shafting consists of a shaft P^1 rigidly connected to the bevel-wheel P; a shaft D^1 , rigidly connected to the hand wheel D, and an intermediate shaft Q which connects with shaft P^1 through a ball-joint R, and with shaft D^1 through a ball-joint R^1 . The device is then operated by turning the hand wheel D, whereby not only the gun 10 A is elevated, but also the sight-bar H is set at the same angle, but opposite to the gun, by means of the shafting D^1 , R^1 , Q, R, P^1 together with the gears P, N and m^1 , h^1 . Of the just mentioned shafting, the shaft 15 P^1 and the ball-joint R are situated entirely within the hollow space of the bracket F, and the shaft Q for the greater part of its length.

The setting of the sight line at a firing 20 angle corresponding to the range is accomplished by turning the spiral gear m^1 by means of the hand wheel D, shafting D^1 , R^1 , Q, R, P^1 and the bevel gear P, N, to adjust the position of the sight bar H, carrying 25 the telescope J, in regard to the elevating-sleeve G, an amount equal to the range. As the gun is simultaneously elevated, the same angle, but in the opposite direction to the sight bar H, the sight line will not 30 change during the described operation. To lay the sight line on the target, is accomplished in usual manner by the use of the hand wheel E.

If, in order to eliminate the influence of 35 the inclined position of the wheels, the worm K is turned, the elevating sleeve G, together with the sight-line will swing around the axis of the spiral gear m^1 . As the spiral gear m^1 , however, remains stationary in 40 consequence of its constrained connection with the elevating gear, which stays unmoved, the angle between the sight-line and the turning axis of the spiral gear will theoretically alter a little, on account of the 45 movement that takes place between the teeth of the sight bar and the spiral rim m^2 . This change in the angle is, however, practically, without any influence in the accuracy of the setting of the sight-bar, because of the 50 nearness in shape to a circle that is given to the spiral rim m^2 , and consequently, at the comparatively small angle (never more than 5° to 7°) required for eliminating the influence of the inclined position of the wheels, 55 the movement will be exceedingly small.

By giving the arm F, which is rigidly connected with the cradle B, a hollow shape, an essential advantage is attained, as the parts P^1 , R, Q of the shafting are particularly well protected, being situated in hollow chamber formed by the arm, so that they, for instance, are well secured against destruction from the enemy's fire.

The invention is evidently also suitable for 60 such guns, where the gear m^1 , for laying the

sight line at an angle corresponding to the range, is operated direct by hand, instead of by means of a hand operating wheel D for elevating the gun. The advantage of using the present invention in this case, 70 would at least be that the construction of the sighting device would be simple and compact.

I claim:—

1. A sighting attachment having a sight bar, a guiding sleeve for said sight bar, a rotary driving gear engaging the sight bar for adjusting it relatively to said sleeve to correspond with the target distance and means for oscillating the sleeve to eliminate the influence of inclined wheel position, the axis of said rotary gear coinciding with the axis of oscillating movement of said sleeve. 75

2. A sighting attachment having a toothed sight bar, a guiding sleeve for said sight bar, a rotary gear constructed with spiral thread engaging the teeth of the sight bar for adjusting the sight bar relatively to said sleeve to correspond with the target distance and means for oscillating the sleeve to eliminate 80 the influence of inclined wheel position, the axis of said rotary gear coinciding with the axis of oscillating movement of said sleeve. 90

3. A gun carriage having an elevating mechanism for the gun barrel and a sighting attachment comprising a toothed sight bar, a guiding sleeve for said sight bar, a rotary gear for adjusting the sight bar relatively to the sleeve to correspond with the target distance, said rotary gear being constructed with spiral thread engaging the teeth of said sight bar and having positive connection with said elevating mechanism, and means for oscillating the sleeve to eliminate the influence of inclined wheel position, 100 the axis of said rotary gear coinciding with the axis of oscillating movement of said sleeve. 105

4. A gun-sighting device having a gear for setting the firing angle to correspond 110 with the target distance and being mounted to permit its sight line to oscillate, for eliminating the influence of inclined wheel position, about an axis that coincides with the axis of the setting gear; means to actuate 115 the device to so oscillate, said sighting device being adjustable parallel to the direction to be imparted to the axis of the gun bore; in combination with a hollow attachment arm upon which the sighting device 120 and said gear are mounted and shafting extending through said hollow arm and having driving connection with said gear.

5. A gun-sighting device having a gear for setting the firing angle to correspond 125 with the target distance, and having its sight-line adapted to oscillate for eliminating the influence of inclined wheel position, about an axis that coincides with the axis of the setting gear; means to actuate the 130

device to so oscillate said sighting device having a toothed segment bar through which it is adjusted and said gear being constructed with a spiral thread engaging the teeth of said segment bar, constructed approximately in the form of a circle.

6. In a gun carriage the combination with an elevating mechanism for the gun barrel of a hollow attachment arm adapted to turn 10 in unison with the gun barrel, a sighting attachment mounted on said hollow arm and comprising a toothed sight bar, a guiding sleeve for said sight bar, a rotary gear constructed with spiral thread engaging the 15 teeth of said sight bar for adjusting the sight bar relatively to the sleeve to corre-

spond with the target distance, and means for oscillating said sleeve to eliminate the influence of inclined wheel position; and shafting extending through said hollow arm 20 and effecting positive connection between said rotary gear and said elevating mechanism, the axis of said rotary gear coinciding with the axis of oscillating movement of said sleeve.

The foregoing specification signed at Bern, this 24th day of September, 1910.

H. KORRODI.
